UNITED STATES PATENT OFFICE.

GEORGE POE, OF NORFOLK, VIRGINIA, ASSIGNOR OF ONE-SIXTEENTH TO R. E. McLAUGHLIN, OF NORFOLK, VIRGINIA, ONE-FOURTH TO HARRIET L. OSTRANDER, OF SOUTH NORFOLK, VIRGINIA, AND ONE-SIXTEENTH TO WILLARD C. BOHLKEN AND ONE-EIGHTH TO WILLIAM H. VENABLE, OF NORFOLK, VIRGINIA.

SAFETY BREATHING-ARMOR.

996,135.

Specification of Letters Patent. Patented June 27, 1911.

Application filed April 27, 1910. Serial No. 558,010.

To all whom it may concern:

Be it known that I, GEORGE POE, a citizen of the United States, residing at Norfolk, in the county of Norfolk and State of Virginia, have invented new and useful Improvements in Safety Breathing-Armor, of which the following is a specification.

This invention relates to improvements in respirators such as are applied to a person before entering a room filled with smoke, or a place in which noxious gases are present.

One object of the invention is the provision of a respirator, including a sleeveless body garment containing a reservoir, and a face mask connected with the reservoir so that the person to whom the device is applied may draw the contents of the reservoir through the connection between the latter and the face mask.

Another object is the provision of a respirator, including a body garment having suitable pockets for the reception of a generating apparatus and also an absorber, communication being established between the generator and reservoir, and also between the absorber and reservoir, a further connection being established between the face mask and absorber, thus permitting the exhaled gas to pass into the absorber, whence it is freed of carbon-dioxid and watery vapors before returning to the reservoir.

With these and other objects in view, that will more fully hereinafter appear, the present invention consists in certain novel details of construction, and arrangement of parts, hereinafter more fully described, illustrated in the accompanying drawings, and more particularly pointed out in the appended claim, it being understood that various changes in the form, proportion, size and minor details of the device may be made, without departing from the spirit of the invention, or sacrificing any of the advantages thereof.

In the accompanying drawings, forming part of the specification: Figure 1 is a front view of a person equipped with my device, showing the generators, absorber and face mask, and also the connections between these parts and the reservoir; Fig. 2 is a back view of a person equipped with my improved device, showing the outline of the reservoir and the connections between the latter and

the head mask, generators and absorber; Fig. 3 is a vertical sectional view of the head mask, also showing a portion of the conveying tube and by-pass; Fig. 4 is a front elevation of the body garment in open position; Fig. 5 is a vertical section taken on the line 5—5 of Fig. 4.

Similar numerals of reference are employed to designate corresponding parts throughout.

The device forming the subject matter of the present invention is shown to include a body garment in the form of an ordinary vest. The front panels of the vest are designated by the numerals 5 and 6 and are connected together by what will subsequently be termed a reservoir. The reservoir is preferably formed of rubber, and, as shown in Fig. 5, a single piece of rubber is doubled upon itself at its medial portion to provide sides 7 and 8, the ends and sides of which are suitably secured together, as shown at 9, to provide air tight joints. The reservoir thus formed will correspond in area to the usual back panel of a vest, it being understood that suitable arm holes, such as shown at 10, will be provided to permit the wearer to apply the vest to his body. By the provision of the sleeveless garment, it will be evident that the movement of the operator's arms will be unhampered.

By reference, now, to Figs. 1 and 4, it will be seen that the panels 5 and 6 are provided with pockets 11 and 12, and arranged in these pockets are generators 13 and 14 for supplying the reservoir with oxygen and nitrogen gases. A Y coupling is designated by the numeral 15 and tubular connections 16 and 17 have their opposite ends connected with the generators 13 and 14 and with the diverging limbs of the coupling; connection between the shank of the coupling and reservoir being established by means of a flexible tube 18, which passes over one side of the wearer and is tapped into the reservoir, as shown at 19, in Fig. 5.

The face mask is shown to include in its construction a semi-ellipsoidal body, designated by the numeral 20, this body 20 being of a sufficient size to house the nose and mouth of the wearer. The base of the body 20 is provided with a peripheral flange 21, and positioned on the upper portion of the

body 20 is a plate 22. The plate 22 is designed to extend transverse the lower portion of the forehead of the wearer and is provided, adjacent to its opposite ends, with 5 openings surrounded by flanges 23 and in which are secured lenses 24.

A pneumatic cushion is designated by the numeral 25 and is positioned on the inner surface of the flange 21, the said cushion being substantially elliptical in contour and having an extension 26 arranged on the inner surface of the plate 22. The cushion 25 and extension 26 are provided with beaded flaps or flanges 27, which bear on the 10 outer surface of the flange 21 and plate 22 to prevent displacement of the cushion. A head strap is designated by the numeral 28 and has its opposite terminals fixedly secured to opposite points on the body 20, said 15 strap being preferably of elastic webbing and serving to secure the mask on the face of the wearer.

By reference, now, to Fig. 3, it will be seen that the body 20 is centrally provided, 25 on its outer face, with a tubular extension 29, said tubular extension surrounding a central opening in the body 20, and threaded into the inner end of said extension is a mouth-piece 30, extending well beyond the 30 cushion 25 so that when the mask is positioned on the face of the operator, the mouth-piece 30 may readily be received in the mouth of the operator. Threaded into the outer end of the section 29 is a nipple 31, the inner end portion of the nipple 31 being counter-bored, as at 32, to provide a valve seat, in which is arranged a spherical check valve 33. The check valve 33 being of greater diameter than the bore of the nipple 35 will of course be prevented against outward movement in the nipple, and inward displacement is prevented by means of a bar 34, extending transverse the counter-bore 32. Connection between the nipple 31 and the 40 reservoir is established by means of a conveying tube 35, the opposite ends of which are connected to the outer end portion of the nipple and the upper end portion of the reservoir, as shown at 36.

50 By referring, again, to Fig. 3, it will be seen that the section 29 is provided at a point between the nipple 31 and the mouth-piece 30 with a radially disposed nipple 37. The outer end portion of the nipple 37 is 55 provided with a counter-bore 38 to provide a valve seat, in which is positioned a spherical check valve 39. Upward and outward movement of the check valve 39 is prevented by means of a cross bar 40.

60 By reference, now, to Figs. 1 and 4, it will be seen that the panel 6 of the vest is provided at a point above the generator 14, with a pocket 41, and arranged in this pocket is a receptacle 42 which contains a quantity of caustic potash. The receptacle 42 is

provided on its upper end with a pair of spaced nipples which receive one end of a by-pass 43, the opposite end of which is received by the nipple 37 and also one end of a tubular return pipe 44, the opposite end 70 of which is tapped into the upper end portion of the reservoir, as shown at 45.

By reference, now, to Fig. 3, it will be seen that the check valves 33 and 39 open alternately, so that when the operator draws 75 through the mouth-piece 30, such action will unseat the check valve 39, thus permitting the mixed gases to pass from the reservoir through the tube 35 and into the mouth of the wearer. When the wearer exhales 80 through his mouth, however, such exhalation will close the check valve 33 and lift the check valve 39, thus permitting the exhaled gases to pass through the by-pass 40 and into the absorber 42, the caustic potash 85 in the latter absorbing the water vapor and carbon-dioxide from the exhaled gases before the latter pass through the return tube 44 and back into the reservoir. Thus it will be seen that the supply of gas from the 90 reservoir may be used for an indefinite period, thus permitting the wearer to remain a long time in a room or other place filled with noxious gases.

When the wearer does not desire to permit the exhaled gases to pass into the absorber, and prefers to exhale through his nose, the exhaled gases may pass to the body 20 in a manner to be presently described;—by referring, now, to Fig. 3, it 95 will be seen that formed in the body 20 and adjacent to the central portion thereof, is an opening, the outer end of which is surrounded by a flange 46 and threaded into the inner end of the opening is a bushing 47. Secured in the outer end portion of the 100 flange 46 is a ring 48, spaced from the adjacent end of the bushing 47, and positioned between the ring 48 and adjacent end of the bushing, is a bodily movable check valve 49. 105 Secured in the outer end portion of the flange 46 is a ring 48, spaced from the adjacent end of the bushing 47, and positioned between the ring 48 and adjacent end of the bushing, is a bodily movable check valve 49. 110 The check valve 49 normally bears on the end of the bushing 47, and formed in the flange 46 and at a point between the valve 49 and ring 48 are radial openings 50. When the check valve 49 bears on the bushing 47, it will be below the openings 50, but when raised from the bushing 47, communication between the exterior and the interior 115 of the body will be established. Thus it will be seen, when the wearer exhales through his nose, that the gases in the body 20 will lift the valve 49 and escape through the openings 50. When it is desired to exhale through the mouth and into the absorber, as before described, the check valve may be 120 rendered secure against accidental movement by means of a latch 52, one end of which is pivoted in the flange 48, and the opposite end of which is receivable by a recess formed 125 at an opposite point in the flange, the in- 130

termediate portion of the latch being provided with a lug 53 which bears on the valve 49 and holds the latter to its seat.

From the foregoing, it will be seen that I have provided a device comparatively simple in construction, inexpensive to manufacture, embodying few parts, and to be so arranged that the danger of derangement is reduced to a minimum.

10. What I claim as new is:

A respirator comprising a sleeveless body garment, an inflatable reservoir sewed into the back portion of the garment, a plurality of pockets arranged on the opposite sides of 15 the front portion of the garment, an absorbent-holding receptacle insertible into one of said pockets, oppositely positioned

gas-holding receptacles arranged in the remainder of said pockets, a face mask, gas-conducting tubes connecting the face mask 20 with the absorbent-holding receptacle, a second gas-conducting tube connecting the absorbent-holding receptacle with the reservoir, the third gas-conducting tube having one end communicating with the reservoir 25 and its opposite end provided with a Y-coupling, and branch tubes connecting the gas-holding receptacles with the Y-coupling.

In testimony whereof I affix my signature in presence of two witnesses.

GEORGE POE.
